UNITED STATES PATENT OFFICE

CLARENCE E. STEVENS, OF CLEVELAND, OHIO, ASSIGNOR TO WHITE SEWING MACHINE CORPORATION, OF CLEVELAND, OHIO, A CORPORATION OF DELAWARE

DESK HINGE

Application filed February 14, 1927, Serial No. 167,881. Renewed May 13, 1930.

This invention relates to desks and has particular reference to school desks of the type having a hinged top or lid which is adapted to be swung upward about an axis 5 at the rear edge of the top to open the desk.

The principal object of the present invention is to provide a simple, durable, inexpensive and efficient friction device to frictionally resist the downward movement of the top so 10 as to prevent likelihood of injury to the fingers or hand of the occupant as might be the case if the top were free to swing down unrestrained.

The above object is attained very effectively 15 by a friction device which acts upon an extension of one of the hinges so disposed as to provide a uniform frictional resistance to the movement of the top in all positions thereof between its normal lowered position and 20 the extreme back position.

The invention may be briefly summarized as consisting in certain novel details of construction and combinations and arrangements of parts which will be described in the specification and set forth in the appended claims. 25

In the accompanying sheets of drawings wherein I have illustrated the preferred embodiment of the invention:

Fig. 1 is a top plan view of a portion of the 30 desk;

Fig. 2 is an end view of the desk omitting the supporting means which is usually attached to the desk body;

Fig. 3 is an enlarged fragmentary sectional view substantially along the line 3—3 35 of Fig. 1 looking in the direction indicated by the arrows;

Fig. 4 is a sectional view substantially along the line 4—4 of Fig. 3 looking in the direction 40 indicated by the arrows;

Fig. 5 is a perspective view of a portion of the desk showing the top swung back to its rearmost position.

Fig. 6 and Fig. 7 are respectively a side 45 view and an end view of one of the hinges.

Fig. 8 and Fig. 9 are respectively a side view and a bottom view of a friction member in the form of a bowed spring which is frictionally engaged by an extension of the 50 hinge.

Referring now to the drawings, 10 represents the body of the desk which is generally formed of sheet metal but may be formed of any suitable material. At the top of the desk is an upper stationary ledge 11 which 55 also may be formed of sheet metal or other suitable material, this being the part which is designed to support the ink well, pencils and like parts. Additionally, the desk includes the usual inclined top or lid 12 which is normally in the position shown in Fig. 2 but is designed to be swung upwardly back beyond the vertical position to give access of the interior of the desk in the manner indicated in Fig. 5. The top 12 is generally 60 formed of wood but, of course, the particular material employed is not at all essential to the invention. 65

The top 12 is hinged at its upper edge to the forward edge of the ledge 11 and for 70 this purpose two hinges, such as indicated at 13, are employed. Only one of the hinges is shown but both will be similarly constructed and mounted, each having a main or body portion 13^a adapted to be secured to the 75 under side of the top portion of the lid 12 with an extension 13^b for connection with the forward edge of the ledge 11, and each having a curved extension 13^c which projects through a slot 10^a in the inwardly extending 80 flange 10^b formed on the end of the body 10 of the desk. At the free end of the curved extension 13^c is a hook 13^d which is adapted to engage the lower side of the flange 10^b in the manner indicated in Fig. 5 to limit the rearward swinging movement of the top or cover 85 12. 85

Coming now to the part more directly involving my invention I form on one of the end walls of the desk body 10 a pocket by 90 attaching to the inner side of the end wall a stamping 14 as most clearly shown in Fig. 5. As will be seen by reference to Fig. 5, the extension 13^c of the hinge extends down into this pocket and it will be apparent that when 95 the top 12 is raised or lowered this extension has an arcuate swinging movement between the walls of the pocket.

For the purpose of frictionally resisting the movement of the top or lid 12 I place in the 100

70 pocket formed by the stamping 14 and the end of the desk body a curved and bowed spring member 15 having a more or less flat face indicated at 15^a which is engaged by the extension 13^c of the hinge and having offset end portions 15^b and also a laterally bent tongue 15^c which bear against the end of the desk body to give the spring stability. The curvature of the spring corresponds substantially to the curvature of the hinge extension 13^c and of the lower part of the stamping 14 and the spring is, therefore, held in place at the bottom of the pocket at all times in position to press yieldingly against the side of the hinge extension 13^c.

75 15 The engagement between this spring and the hinge extension is such as to give just the requisite frictional resistance to the movement of the lid or top to keep it from falling by gravity if released in any position. A further feature of importance is the fact that the frictional device is inexpensive to construct and to apply to the desk and it has an indefinite life, there being nothing to get 80 out of order.

85 25 While both hinges are constructed alike as already explained and while this frictional device may be employed in conjunction with both hinges I find that satisfactory results are obtained by the application of a movement resisting spring of the character stated on the inner side of one of the end walls only of the desk body so as to frictionally engage the extension on one of the hinges.

90 35 Having thus described my invention, what I claim is:

95 40 1. In combination with a fixed element having an opening therein and a swinging closure therefor, hinge members for said closure pivotally supported upon said fixed element, one of said hinge members having an extension projecting into said opening along the adjacent end thereof, and a resilient sheet metal friction member arranged between said extension and the associated end wall of said opening and adapted to provide an increasingly greater contact area as said closure approaches closed position, said end wall acting as a backing for the friction member.

100 45 2. In combination with a fixed element having an opening therein and a swinging closure therefor, hinge members attached to said closure and pivotally connected to said fixed element, one of said hinge members having an extension adapted to swing within the opening alongside the adjacent end wall thereof, a pocket formed on the inner side of said wall, a loose friction member seated in 50 said pocket and engaged on one side by a side wall of the pocket and on the other by the extension of the associated hinge, the amount of contacting surface between said extension and friction member increasing as 55 said closure approaches closed position.

105 5. A desk hinge construction comprising a hinge member adapted to be secured to the lid of a desk and having an arcuate extension arm adapted to swing along the inner side of the end wall of the desk, a casing adapted to be secured to said end wall to form a pocket, and an arcuate spring mounted within said casing and adapted to have a backing against one side of said pocket, said spring being fixed against bodily movement and being adapted to contact the end of said extension arm throughout its travel within the pocket.

110 6. A desk hinge construction comprising a hinge member adapted to be secured to the lid of a desk, and having an arcuate extension arm adapted to swing along the inner side of the end wall of the desk, a casing adapted to be secured to said end wall to form a pocket, and an arcuate spring loosely mounted within said pocket adapted to have a backing against one side of the pocket and to frictionally engage said extension arm.

115 7. In testimony whereof, I hereunto affix my signature.

CLARENCE E. STEVENS.
